2 SHEETS—SHEET 2.

UNITED STATES PATENT OFFICE.

THOMAS DEAN, OF INDIANAPOLIS, INDIANA.

PASTING DEVICE.

1,396,998.

specification of Letters Patent.

Patented Nov. 15, 1921.

Original application filed June 28, 1918, Serial No. 242,483. Now Patent No. 1,336,944. Divided and this application filed December 15, 1919. Serial No. 344,957.

To all whom it may concern:

Be it known that I, THOMAS DEAN, a citizen of the United States, and a resident of Indianapolis, county of Marion, and State 5 of Indiana, have invented a certain new and useful Pasting Device; and I do hereby declare that the following is a full, clear, and exact description thereof, reference being had to the accompanying drawings, in 10 which like numerals refer to like parts.

This invention relates to a machine for making flexible book covers and more particularly to the pasting device for the same. This invention is a divisional application of 15 the co-pending application entitled Machine for making book covers, Serial No. 242,483, filed June 28th, 1918, and patented April 13, 1920, No. 1,336,944.

The chief object of this invention is to 20 hold the covering material in position while the adhesive substance is automatically applied thereto.

The full nature of the invention will be 25 understood from the accompanying drawings and the following description and claims:—

Figure 1 is a top plan view of the pasting device, the same being incorporated in a 30 cover forming machine. Fig. 2 is a vertical longitudinal sectional view of the pasting device showing the operating parts in side elevation. Fig. 3 is a vertical transverse sectional view of the pasting device, parts being 35 broken away. Fig. 4 is an enlarged top plan view of the adhesive applying mechanism. Fig. 5 is a sectional view thereof as 40 seen on line 5—5 of Fig. 4, with the parts in inoperative position. Fig. 6 is a similar view with the parts in the operative position. Fig. 7 is a sectional view of the 45 paste reservoir, which shows the manner of operating the adhesive applying mechanism.

In the drawings similar reference numerals refer to corresponding parts, and so 45 far as possible refer to similar parts in the co-pending application referred to.

In the drawings 1 indicates a frame of 50 the desired construction, the same being provided with a platform 2 and end walls 3 and 4. A pair of endless link chains 12 extend around sprocket wheels 13 and are carried by the platform 2, the endless conveyer being provided with suitable gripping devices with which the cover is positioned be-

neath the pasting device to receive the adhesive. 55

The adhesive applying mechanism comprises a plate 25 in the lower face of which are formed channels 26 and 27, and in said channels is mounted a clamping frame 28 and an adhesive applying frame 29 respectively, the lower face of the adhesive applying frame being preferably provided with corrugations 30 in order to obtain and apply a greater amount of the adhesive material. 60 The clamping frame 28 is forced downwardly by means of plungers 31 which extend upwardly through the plate 25 and are hollow at their upper ends to receive stems 32 which are attached at their upper 65 ends to cross bars 33, said cross bars being adapted to receive pressure to force the plungers downwardly and move the clamping frame into engagement with the covering material. 70

The clamping frame 28 is normally returned into the channel 26 by a spring 34 around the upper portion of the plunger 31, the upper end of said spring pressing against the collar 35 of the plunger. The 75 stem 32 is slidable in the plunger 31 and is normally held in elevated position by means of the spring 36, one end of which engages the upper face of the collar 35, while the opposite end presses against the lower face of 80 the cross bar 33. The adhesive applying frame 29 is forced downwardly by means of plungers 37, the upper ends of which are connected with the cross bar 38, the frame 29 being normally held seated in the channel 85 27 by springs 39 around the plungers 37, between the plate 25 and the cross bars 38. 90

The frames 28 and 29 are operated by means of rocking levers 40 which are pivoted between their ends to standards 41, the 95 inner ends of said levers having curved projections 42 and 43 which engage respectively with the cross bars 33 and 38. These levers, when rocked upon their pivots in one direction, force downwardly the plungers 100 31 and 37 and cause the frames 28 and 29 to engage with the covering material 7. The frame 28 holds the cover in position upon the movable platform 44, see Fig. 6, while the frame 29 applies the adhesive to the covering material. The movement of the platform 44 is secured by suitable means illustrated and described in detail in the patent 105

hereinbefore mentioned, and reference being had thereto. The levers 40 are rocked upon their pivot pins to operate the frames 28 and 29 through the medium of stationary heads 45 and the adjusting screws 46 carried by the outer ends of the rocking levers 40, coming in contact with the heads 45 as the plate 25 is lowered.

The levers 40 are so arranged that the plunger 31 and the clamping frame 28 attached thereto will be moved into engagement with the covering material 7 before the pasting frame 29 carrying the adhesive substance is engaged with the covering material. Since the compression of the springs 36 is greater than the springs 34 and the compression of the springs 39, the frame 28 will remain in engagement with the adhesive applying material 7 until after the covering frame 29 has been disengaged therefrom, thereby preventing the covering material from being carried upwardly by the frame 29, the frame 29 leaving a quantity of adhesive material on the surface of the covering material. The movable platform 44 is held yieldingly in position by means of springs 47 (see Fig. 2) so that the corrugated lower face of the frame 29 will not be injured by pressing too firmly against the movable platform when the frame is lowered to place the adhesive on the covering material.

Means for supplying adhesive to the corrugated face of the frame 29 is herein shown comprising a trough 48 for the reception of any suitable adhesive substance. The ends of the trough are slidably mounted in grooves 49 formed in the frame 50. The transverse roller 51 is rotatably mounted in the trough 48 and projects above the upper edge of the trough, so that as the trough is moved back and forth between the frame 29, the face of the roller will engage the face of the frame and transfer a coating of adhesive material thereon. It will be understood that the endless chains 12 have a reciprocating movement across the face of the platform 2. The trough 48 is moved back and forth below the frame 29 through the medium of a latch 52, see Fig 7, which is pivoted to a part of the trough and is so arranged that one or the other end thereof will extend in the path of a lug 53 carried by the chain 12. When the latch is in the position shown in Fig. 7, the lug 53 will engage one end of the latch and cause the trough to travel with the chain as the grippers are being moved for engagement with the sheet of covering material. When the trough reaches the end of this lateral movement, the inclined face 54 of the latch will engage the trip pin 55, so as to permit the lug to pass out of engagement with the latch and continue its travel with the chain 12, while the trough remains stationary.

This operation disposes the opposite end of the latch in the path of the lug 53, so that when the reciprocating chain 12 is on its return stroke, the lug 53 will engage the latch 52 and return the trough to its initial position, the tapered face 56 engaging a trip pin 57 at the opposite end of the frame 50, thus again releasing the latch from the lug and permitting the chain to continue its travel while the trough remains stationary. Any suitable means may be provided for holding the latch in its tilted position, or against swinging movement, such as a spring 58 which is carried by the trough and presses against one face of the latch. The plate 25 and the frame members carried thereby are lowered into engagement with the sheet of covering material 7, in order to apply adhesive substance thereto through the medium of rods 104, (see Figs. 2 and 3), the upper ends of the rods being attached to parts of the base plate 25, while the lower ends of the rods are connected to the cross bar 105. The ends of this cross bar are provided with studs 106 which engage cam channels 107 in the cam wheels 108, suitably and rotatably mounted in the frame 1.

Means for operating the chain is herein shown in dotted lines in Fig. 2, and comprises a train of gears 143, 144, 145, 146 and 147, the latter gear coöperating with the segmental rack 148. The segmental rack is carried by a lever 149, the lower end of which is pivoted, so that by swinging the rack in the arc of a circle, the train of gears 143, 144, 145, 146 and 147 will be rotated in the opposite direction. Means for rocking the segmental rack comprises a pitman 150, one end of which is attached to the lever 149 midway its ends, the opposite end of the pitman being pivoted eccentrically upon the face of the disk 134, thus giving the lever 149 a rocking motion when the disk 144 is rotated.

The invention claimed is:—

1. In a machine for making book covers, the combination with a chain structure adapted to convey a sheet of covering material, and means to apply adhesive substance to the edges of the covering material, of a trough for containing adhesive substance, and means coöperating with said trough for engagement with parts of said chain structure for moving the trough back and forth below the adhesive applying means for depositing a coating of adhesive substance thereon.

2. In a machine for making book covers, a frame for applying an adhesive to parts of the covering material, said frame having corrugations in its lower face.

3. In an adhesive applying machine, the combination of adhesive applying means, holding means for holding stationarily a sheet to be pasted during the adhesive ap-

plying operation, a single common means for actuating said adhesive applying means and said holding means, comprising pivotally supported lever means, means for 5 tilting said lever means, and other means associated with said lever means and said adhesive applying means and said holding means for actuating the same in timed relation.

10 4. In an adhesive applying machine, the combination of adhesive applying means, holding means for holding stationarily a sheet to be pasted during the adhesive applying operation, means for actuating said adhesive applying means and said holding means, comprising pivotally supported lever means, adjustable means for tilting said lever means, and other means associated with said lever means and said adhesive applying means and said holding means for 15 actuating the same in timed relation.

20 5. In an adhesive applying machine, the combination of corrugated adhesive applying means, holding means for holding stationarily a sheet to be pasted during the adhesive applying operation, means for actuating said adhesive applying means and said holding means, comprising pivotally supported lever means, means for tilting 25 said lever means, and other means associated with said lever means and said adhesive applying means and said holding means for actuating the same in timed relation.

30 6. In an adhesive applying machine, the combination of corrugated adhesive applying means, holding means for holding stationarily a sheet to be pasted during the adhesive applying operation, means for actuating said adhesive applying means and said holding means, comprising pivotally supported lever means, adjustable means for tilting 35 said lever means, and other means associated with said lever means and said adhesive applying means and said holding means for actuating the same in timed relation.

40 7. In an adhesive applying machine, the combination of a yieldingly mounted sheet supporting platform, adhesive applying means, holding means for holding the 45 pasted sheet stationary upon the sheet supporting platform during the adhesive applying operation, means for actuating said adhesive applying means and said holding means, comprising pivotally supported lever 50 means, means tilting said lever means, and other means associated with said lever and said adhesive applying means and said holding means for actuating the same in timed relation, said sheet supporting platform being engageable by said adhesive applying means and said holding means through the 55 sheet to be pasted.

60 In witness whereof, I have hereunto affixed my signature.

THOMAS DEAN.
